CLAIM

The ornamental design for a controller for an electronic device, as shown and described.

DESCRIPTION

FIG. 1 is a front-top-right perspective view of a controller for an electronic device according to an embodiment of my new design;

FIG. 2 is a rear-bottom-left perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a partial front-top-right perspective view thereof as indicated in FIG. 8.

The dot-dot-dash broken lines indicate the boundary of the enlarged portions of the drawings. The remaining broken
